UNITED STATES PATENT OFFICE.

LAWRENCE EDWARD KILLIAN, OF FILLMORE, ILLINOIS.

CROSSCUT-SAW EQUALIZER.

1,387,274.

Specification of Letters Patent. Patented Aug. 9, 1921.

Application filed February 10, 1921. Serial No. 443,867.

To all whom it may concern:

Be it known that I, LAWRENCE E. KILLIAN, a citizen of the United States, and a resident of Fillmore, in the county of Montgomery 5 and State of Illinois, have invented a new and Improved Crosscut-Saw Equalizer, of which the following is a full, clear, and exact description.

This invention relates to improvements 10 in cross cut saw equalizers, and more particularly to an attachment for a cross cut saw which enables a single operator to efficiently operate the saw, giving him the necessary purchase and leverage so that he 15 can effectually use the saw in any cutting position.

A further object is to provide an equalizer 20 which can be conveniently attached to any ordinary saw, which will be relatively cheap to manufacture, and which will most efficiently perform the functions for which it is intended.

With these and other objects in view the 25 invention consists in certain novel features of construction, and combinations and arrangements of parts as will be more fully hereinafter described and pointed out in the claims.

In the accompanying drawings—

30 Figure 1 is a view in elevation illustrating my improved equalizer in position on a cross cut saw.

Fig. 2 is an end view of the saw with the 35 equalizer thereon.

Fig. 3 is a detail perspective view of the 40 handle end of the saw with the equalizer handle in position on the saw.

1 represents a log and 2 an ordinary form 45 of cross cut saw shown in position for cutting the log. This cross cut saw is provided, as is customary, with a handle 3 at one end which projects upwardly and at right angles to the saw.

My improved equalizer comprises a pair of 50 relatively long handles 4 and 5 having beveled outer ends 6 to which a spring strip 7 is secured by bolts 8 or other attaching means. The handle 4 has a bifurcated end 9 which straddles one end of the saw 2 and 55 is secured to the saw by means of a bolt 10

and nut 11. The handle 5 also has a bifurcated end 12 which straddles the saw 2 adjacent the handle 3 and a relatively small metal plate 13 is secured to the extreme end of the bifurcated portion 12 of handle 5 55 under the cutting edge of the saw 2 so as to effectually hold the handle 5 in place.

When the device is in use on a saw, the operator grasps the handle 3 with one hand and the handle 5 with his other hand, and 60 by reason of these two gripping points, the saw can be conveniently and effectually manipulated from one end. If occasion may require, another operator may grasp the handle 4 to assist in the operation, but in 65 most cases a single operator at the handle end 3 of the saw can conveniently operate the same to cut timber in any ordinary position.

Various slight changes might be made in 70 the general form and arrangement of the parts described without departing from the invention, and hence I do not limit myself to the precise details set forth, but consider myself at liberty to make such changes and 75 alterations as fairly fall within the spirit and scope of the appended claims.

I claim:

1. An equalizer of the character described, 80 comprising a pair of handles having bifurcated ends adapted to receive the respective ends of a saw and connected thereto, said handles adapted to be disposed at an angle to the saw blade and having beveled outer ends, and a flat spring strip secured at its 85 ends to the beveled faces of the respective handles.

2. The combination with a saw of the 90 character described having a handle at one end, of an equalizer independent of the saw and handle and comprising a pair of equalizer handles bifurcated to receive the saw blade, a bolt securing one bifurcated end to the saw blade, a plate secured to the other bifurcated end and located against the 95 toothed edge of the saw, and a spring connecting the free ends of the equalizer handles and holding one of said equalizer handles against the saw handle.

LAWRENCE EDWARD KILLIAN.
